INTERPOSED DISK RHEOSTAT

Newton C. Schellenger, Elkhart, Ind., assignor to
Chicago Telephone Supply Company, a corpora-
tion of Indiana

Application May 1, 1933, Serial No. 668,757

10 Claims. (Cl. 201—48)

My invention relates to control devices for electrical circuits, and, more particularly, to variable resistance devices of the general type set forth in my prior Patent No. 1,851,933, granted March 5 29, 1932.

The present application is directed toward improving variable resistance devices of the intermediate contact disk type, and especially those that are exceedingly small and compact.

10 Heretofore, in the types of devices characterized above, it has been impossible to obtain a clear, sharp, well defined line of contact between the contacting disk and the resistance element. This has been particularly true in devices of this 15 type wherein the diameter or width of such devices is quite small; i. e., not in excess of three inches.

This condition has been due to the fastening means employed between the contact disks or 20 rims and their central hubs. These fastenings usually were straight, radial spokes, which were necessarily short to conform with the requirements of the small mountings and casings within which they were assembled.

25 In the radial spoke type of intermediate disk, when the rim is depressed intermediate any two of the spokes, the spokes bend at portions along their length. These increments of bent portions lie within, or parallel to, chords of a circle lying 30 within the rim, and to which chords, the longitudinal axis of the depressor arm is always substantially normal. This action causes the entire segment of rim subtended by the major chord to be depressed downwardly toward the resistance 35 element, and a considerable amount of the entire depressed segment actually engages the resistance element. Thus, if a substantially planar resistance element is employed, a fine, well defined line of contact cannot be effected, and a sensitive 40 variation in resistance values is rendered impossible.

Another difficulty in the prior art has been encountered in the connecting of flat, carbonaceous 45 resistance elements to terminals by means of rivets, screws, etc. It is necessary that some such fastenings be utilized to effect contact between the resistance element and the terminals at the high and low resistance ends of the element. This has been done heretofore by appropriating the extreme end portions of the resistance element to 50 fasten, by means of large headed rivets that project above the contact surface, the resistance element and terminals to the base. This type of assembly necessitates the forfeiture of that portion of the resistance element underlying the fas-

tenings, as well as portions lying beyond the fastenings, which, of course, means a sacrifice of effective resistance.

Other ways, equally as troublesome, have been tried without success. One of these contemplated 5 countersinking a cylindrically-headed rivet in a complementary aperture in the base, to permit the passage of the contactor member thereof. It was found, however, to be impossible to obtain a smooth connection surface between the rivet and the resistance, since either the rivet head would project and engage the contactor prematurely to short-circuit some effective resistance, or else it would fail to touch at all, (being countersunk too great a depth), whereby a high minimum resistance value resulted at the low resistance terminal. 10

In combination variable resistance and power switch units, wherein both devices are controlled 20 by a single actuating shaft, there has heretofore been a further sacrifice of effective resistance. The switch mechanism was caused to be actuated over a portion of resistance element adjacent the low resistance end, which means that the switch was caused to open the circuit before maximum 25 low resistance position could be reached by the contactor; and, conversely, when the contactor was moved from the extreme low resistance position, a substantial amount of the resistance element was traversed before the switch was actuated to close the circuit. Thus, a considerable 30 amount of otherwise effective resistance was rendered totally unusable.

Covers or housings for devices of the character described, and particularly those covers 35 adapted to carry power switches, have been the source of much consternation and worry in the trade.

First, it was necessary to provide proper spacing means between the cover and the variable resistance device, to insure that parts of the switch and resistance device were in proper cooperative relation. Secondly, there had to be provided means to retain the cover in positive engagement 40 with the variable resistance device to insure against any relative movement therebetween. Thirdly, to position the cover, provision had to be made for terminals and other projections extending from the variable resistance device. These necessitated the provision of apertures, 45 which permitted dust, dirt and other foreign matter to find its way into the casing to the detriment of the sensitive parts therein contained.

Therefore, it is an object of my invention to 50 provide a variable resistance device of the inter-

posed contacting disk type wherein contact of the disk with the resistance element approaches a linear tangency as a limit.

It is another object of my invention to provide a 5 contacting disk for variable resistance devices of the interposed contacting disk type, that is highly flexible and which is capable of having peripheral portions distorted out of their normal plane without disturbing the position of its other portions.

It is still another object of my invention to provide a durable, inexpensive cover for a variable resistance device, which has novel means for engaging the base of such device for retention there- 15 on.

It is a further object of my invention to provide novel means for spacing portions of a cover from portions of a variable resistance device in predetermined relation, and to render said cover 20 dust-proof.

It is still a further object of my invention to provide for fastening a flat carbonaceous resistance element to a base member by means lying within the path of the contactor of a variable re- 25 sistance device without affecting the predetermined resistance gradient of the element.

It is still a further object of my invention to provide a combined variable resistance and power switch unit wherein the switch is actuated when 30 the contactor arm is not in contact with any portion of the effective resistance.

With the above and related objects in view, my invention consists in the following details of construction and combination of parts, as will be 35 more fully understood from the following specification, when read in conjunction with the accompanying drawings, in which:

Figure 1 is a perspective view of a variable resistance device constructed in accordance with 40 my invention, illustrated with the cover removed;

Figure 2 is a top plan view of Figure 1;

Figure 3 is a mid-sectional view of the variable resistance device and cover having a switch mounted thereon; the switch not being shown in 45 section;

Figure 4 is an exploded perspective view of the variable resistance device and cover illustrating the relation of parts and order of assembly;

Figure 5 is a top plan view of a modified form 50 of a pressure arm;

Figure 6 is a sectional view taken on the line 6—6 of Figure 5;

Figure 7 is a plan view of the pad holding blank;

Figure 8 is a side view of the modified pad 55 holder;

Figure 9 is a fragmentary exploded sectional view of a holding structure at each end of the resistance element;

Figure 10 is a fragmentary assembled view of 60 the elements shown in Figure 11;

Figure 11 is a bottom plan view of the assembly shown in Figure 10, more clearly showing the peened over holding bolt;

Figure 12 is a modified form of pad holding 65 blank;

Figure 13 is a side elevational view of the modified pad holder made from the blank shown in Figure 12; and

Figure 14 is a bottom plan view of the modified 70 pad holder shown in Figure 13.

Referring in detail to the drawings: An insulating base A, generally circular in formation, has mounted upon one face 10, near its periphery, a circularly disposed resistance element B of the 75 carbonaceous type, although a wire wound resist-

ance element arcuately disposed may readily be employed.

A sleeve or journal bushing C extends through an opening 12 in the base. The bushing C may serve as a mounting device for the unit, by being 5 threaded at one end 14 for the reception of a nut by which the assembly is clamped upon a suitable bracket.

The bushing C contains an enlarged head 16 disposed against the surface of the base upon 10 which the resistance element is located, and if desired this head 16 may be serrated or knurled as shown at 18, see Fig. 3, so that it will bite into the base to prevent any relative rotary movement 15 between the base and bushing.

A shoulder 20 of the bushing protrudes through the base opening and also through a holding clamp H and the free end of the shoulder is expanded to grip one face of the clamp for the prevention of longitudinal motion and to grip a plurality of spaced niches 22 of the clamp for the prevention of rotary motion. An annular shoulder 24 disposed interiorly from the enlarged head 16 constrains an insulating washer D upon which an interposed low resistance flat contact disk E 25 rests.

The flat disk E is preferably comprised of a rim 26, and a hub portion 28 which are connected by a plurality of flexible serpentine spokes 30. The spokes are substantially of uniform width from the center hub to the rim but take a circuitous path from the hub to the rim in substantially an S-shape. The spokes are positioned so that deflection of the disk under a given pressure will be substantially the same at any point along the circumference. An electrical conductor tab 32 is formed upon the hub by cutting away the surrounding area. A plurality of positioning ears 34 are also formed on the hub by a punch press operation, and the ears tightly grasp notches 36 in 40 a positioning insulating washer F, to prevent radial movement of the disk.

The spokes are highly flexible and yieldable, and due to their serpentine configuration, are almost twice as long as they would be were they 45 disposed along radii of the disk throughout their entire length. The increased length of serpentine spokes over radial spokes increases the effective flexibility of the spokes. The rim supported by them, being held by such highly flexible media, 50 is permitted far greater freedom of movement than has heretofore ever been possible.

The advantages of this increased flexibility may better be seen by comparing these types of devices with those of the prior art. A rheostat of 55 small diameter, having an interposed contactor disc of the radial spoke type, will upon actuation of the contactor arm, short circuit a considerable amount of the effective resistance. The short, stiff spokes tend to hold the rim rigidly between them, whereupon, when the rim is depressed in one portion, a substantial segment of the rim is caused to follow the depressed portion to engage the resistance element for a considerable distance adjacent the contactor arm. Thus, a sharp or delicate line of contact is made impossible, and a considerable amount of the effective resistance is short-circuited.

The serpentine spokes, however, permit the 70 rim to be rather abruptly distorted out of its normal plane at the point of contact without disturbing to any material extent the planar disposition of its remaining portion. In this manner, a fairly sharp line of contact is obtained, and 75

the short-circuiting of effective resistance is minimized.

The disk E and the washer F are secured in place by turning over or peening the end 35 of the bushing against the washer F. If desired, a metal washer may be placed over the washer F to prevent breakage of the washer F provided it is made of fragile material.

A pressure or wiper arm G, of the general type 10 shown in my application filed January 31, 1930, Serial No. 424,775, which has matured into Patent No. 1,913,686, may conveniently consist of a central portion 38 secured to the end of a shaft 39 as by heading over the splined end of the 15 shaft. A crescent-shaped arm 40 has its ends connected to the central portion by the bight portion 42. A tongue 44, carrying a pressure pad 43 and projecting from the crescent arm 40, is adapted to strike radially projecting ears 46 of 20 the cup-shaped housing or covering J, in order to limit the rotation of the arm.

The pressure pad may be secured to the under side of the arm and may, however, take a variety of forms. In the form shown in Fig. 4, the pad 25 is formed of a cylindrical block of material, such as oil impregnated leather, and is held in an inverted cup in any desired manner.

In Figure 5, another modification of the pressure arm and the pad holder is shown. An 30 aligned opening 50 and a notch 52 are cut into the crescent-shaped arm 40, and a metal strip 56 is formed to have one end 58 of U-shaped formation, in order to grasp a suitably shaped pressure pad 60 and to fit into the notch 52. The 35 other end is offset at 61 and suitably passes through the opening 50. The tongues 62 and 64, protruding radially from the periphery of the crescent-shaped arm 54, push the pad around the rim 26.

40 Wings 66 and 68, see Figs. 7 and 8, are formed transversely of one end of the strip 56 to firmly grasp the pressure pad 60.

The housing J has an insulated strip liner K disposed upon the inner peripheral surface, to 45 provide a substantially dust-proof housing, to guard any "live" parts from coming into contact with the housing or shell, and to cover the gap or space between the housing and the terminals. A plurality of slots 70 in the liner K have the stop 50 members 46 of the housing completely pass therethrough and occupy the space defined therein.

The housing J, within which the rheostat is housed, is provided with a plurality of projecting tongues 72 of sufficient length to be bent over 55 to attach the housing to the plate A. An elongated notch 74 is cut in the free end of the cylindrical wall of the housing. The base A has an arcuate peripheral extension 76 through which suitable terminals pass and the peripheral extension is constructed to interfit with the notch 74 of the housing. The registration of the extension of the base and the notch 74 in the housing with the plate A accurately aligns the cover with respect to the plate both in a rotary direction about the axis of the shaft and in a direction along the shaft.

60 The elongated notch 74 of the housing J provides some clearance over the terminals to prevent any short circuit and the clearance is filled 65 by the insulated strip liner K.

The liner K, is of such breadth that it will extend from the end wall portion of the housing J, down the inner face of the side walls thereof to a peripheral line near their open end. This peripheral line is spaced from the free edge of the 70

cylindrical side walls a distance substantially equivalent to the thickness of the base member A. Since the housing is of such size and configuration as to snugly telescope upon the base member A, the liner K, being disposed around the inner side walls of the housing, diminishes the inside diameter thereof to such a degree that it is less than the mean diameter of the base A; hence the housing is unable to telescope over the base beyond the strip's edge. 10

Thus, it will be seen that the lower edge of the liner forms a bearing shoulder which abuts the base member adjacent the edge of its inner face, and since its upper edge abuts the inner face of the end wall of the housing, it serves as 15 a spacer to maintain the housing, base and associated parts in predetermined spaced relation.

When the cover is placed on the base so that notch 74 registers with the terminal mounting extension of the base, the insulating liner strip 20 K, being of the same breadth throughout, closely engages the base member around its periphery, and closes the notch 74 which overlies the terminals.

25 The liner, being of flexible material, closely adheres to all portions of the base, and adjusts itself to all irregularities thereof to render the casing dust-proof.

The ears 12 are then crimped over to engage the base whereby a compact, rigid and dust- 30 proof unit is provided.

The advantage of the ears 12 is manifest in assembling the unit when a liner strip is employed. The press that crimps the ears into engagement with the base first forces the base 35 into firm engagement with the edge of liner K, and then crimps the ears over to maintain the parts in this firm engagement. Since this is all done by one operation, a material saving of time and material is effected over the old types of 40 fastening means, and a far superior product results therefrom.

Although the resistance element base is annular in formation, the effective conducting surface of the resistance element is arcuate in formation, leaving but a small arc ineffective. This small ineffective arcuate distance is utilized for the transient movement of the pressure arm during the closing of the switch. Heretofore, combined switches and variable resistance devices 45 have been so constructed that the switch was actuated over an effective portion of the resistance. Thus when the contactor arm was moved from its point of lowest resistance, the switch moved to closed position, but not before the contactor arm had traversed a substantial amount of the effective resistance. Likewise, when it was desired to move the contactor arm to its extreme low resistance position, the switch would be actuated into open position to break the circuit before this could be effected. Consequently, a substantial amount of the effective resistance was rendered useless. In my present structure, this fault is entirely overcome. 55

60 It is essential that the entire upper surface of the resistance element base lies substantially in the same plane, otherwise the rim of the low resistance interposed disk will be bent and a kink permanently established therein.

65 The base portion is provided with apertures 78 70 and 80 which are of such size as to receive rivets 82 and 84. The edges of the apertures adjacent the inner face of the base are beveled to form tapering countersunk portions. The resistance element having rivet apertures of the same size 75

overlying the base apertures 78 and 80, is drawn down into the tapered countersink by the tapered portion of the rivet head. The resistance element in this position forms a lining for the 5 countersink and coacts with the rivet head to effect a perfectly tight, smooth fit. The rivet head being flush with the resistance element's contact surface permits the contactor member to pass beyond the effective resistance area during 10 the actuation of the switch mechanism.

The openings 86 and 88 through the conducting ends of the resistance element, see Figs. 4, 9 and 10, are of the same diameter as the openings 78 and 80 through the base, and as the rivets are 15 of electrical conducting materials, the electrical circuit from the ends of the resistance element to the outside terminals 90 and 92 will be completed.

In order to prevent any damage to the resistance element great care must be exercised in fastening the rivets 82 and 84 to the ends of the 20 resistance element. The most suitable manner is to expand the tip 94 of the bolt at a plurality of points 96, 98, 100, and 102 as shown in Figs. 9, 10 and 11.

A rivet 104 of conducting material, see Fig. 3, 25 attached to the tab 32 of the flexible disk E and an intermediate electrical terminal 106 provides the electrical take-off for the variable contact on the resistance element.

30 *Switch operation*

My rheostat may, also, be used in conjunction with the operation of a snap switch S, whereby a rotary or oscillatory movement of the pressure arm over a short peripheral length of the circumference actuates operably connected mechanism to open or close the snap switch. However, the relationship of the switch to the rheostat is such that none of the effective conducting surface 35 of the resistance element between the zero resistance terminal and the maximum resistance terminal is contacted by the interposed member upon movement of the pressure arm, during the 40 operation of the switch.

In order to provide for the operation of the 45 switch or circuit controller, the pressure or wiper arm G may be provided with a normally projecting, insulated, eccentrically mounted pin 108, see Figs. 1 and 3. This pin 108 projects normal to 50 the plane of the pressure arm G and into such position that it may transiently engage an operating ear 110 of the switch mechanism S. A transient movement of the pressure arm G will therefore operate the switch mechanism. The switch 55 S, shown by way of example, may be any preferred type of switch suitable for this purpose, such as for example the switch shown in my copending application Serial No. 602,006, filed March 30, 1932, to which application reference is 60 here made for the details of construction of the switch and the manner of mechanical arrangement.

Terminals

As will be best seen in Figures 1, 2, 3 and 4, 65 the terminal member 106, and the same details of construction apply to the terminals 90 and 92, of a single strip of conducting material of uniform thickness, has a foot 112 connected, by means of the bolt, rivet, or eyelet 104 which pierces 70 the base, to the tab of the interposed disk which forms the intermediate variable contacting conductor. The foot 112 of the terminal is disposed upon the outer face of the base A and has a neck 114 therefrom bent normal to the plane of the 75 base. The neck fits within a suitable slot 116 in

the mounting plate to prevent the terminal member from being turned with respect to this plate. Shoulders 118 and 120 extend from the neck 114 of sufficient width to rest and engage the opposite face of the mounting base A so that movement of 5 the terminal in any direction is prevented. The shoulders then taper or merge into a lug portion until the notch or eye 122 is reached, thus when the various lead wires are being attached to the terminals there can be no inadvertent bending 10 of any of the terminals so that the terminal rivets may be disturbed which might result in an increased minimum resistance, particularly at the low resistance end of the resistance film.

Furthermore, the terminal arrangement here- 15 inbefore described prevents the inadvertent pressing of the terminal against the metal panel for the radio set to complete a short-circuit which short-circuit may do considerable damage during the testing or inspection of the radio set. 20

My preferred form of rheostat construction lends itself quite readily to the tandem or double type of rheostat in which a second or duplicate rheostat structure is placed over the first rheostat in place of the cover J. 25

In Figure 12 is shown another modification of the pad-holder blank. A tail 200 merging into a body portion 202 has material for wings 204 and 206 at each end adjacent a head portion 208. Upon forming the blank, as shown in Figures 13 30 and 14, the tail 200 is offset from the body 202 and the head 208 is bent in a U-shaped formation which together with the wings 204 and 206 forms a basket or receptacle for the pad, which pad preferably may have irregular sides. 35

Although this invention has been described in considerable detail, such description is intended as illustrative rather than limiting, as the invention may be variously embodied, and the scope of the invention is to be determined as claimed. 40

I claim:

1. In a variable resistance unit, in combination, a base member, a resistance element mounted on said base member, a contactor device adapted to be moved to vary the effective resistance of said element, and a metallic cup-shaped cover secured to said base member to overlie said resistance element and contactor device, the side walls of the cup-shaped cover extending beyond the edges of the major portion of the base member, the cover being spaced relative to the base member by an upstanding cylindrical band of insulation disposed adjacent inner side wall portions of said cover. 45

2. In a variable resistance device, a circular base member having a resistance element and a contactor mounted thereon, a cylindrical cup-shaped casing telescoped snugly upon said base member to overlie said resistance element and contactor, the side walls of the cup-shaped cover 50 extending beyond the edges of the major portion of the base member, a band of insulation disposed around the inner periphery of the side wall portion of the casing and being of less width than said side wall portion, the edge of said band adjacent the open end of the casing being adapted to engage the inner surface of said base member. 55

3. In a circuit controller unit, a base member having circuit controlling devices mounted thereon, terminal members projecting outwardly from 60 said base member, a metallic cover telescoped upon said base member having an aperture therein to provide clearance from terminal members, and a band of insulation interposed between portions of said cover and said base member to main- 65

70

75

80

85

90

95

tain a predetermined spaced relation therebetween and to close said aperture.

4. In a variable resistance device, a base member, a resistance and movable contactor carried thereby, a cup-shaped metallic casing, having ears depending from its free edge, telescoped upon said base member to overlie said resistance and contactor, a strip of insulation lining the side walls of the casing which is of less width than said side walls, the edge of said strip adjacent the open end of the casing adapted to engage the inner surface of said base member adjacent its edge, said ears being bent to engage the outer surface of said base at peripheral points to hold said strip and base member in firm engagement.

5. A variable resistance unit comprising a base member, resistance varying means mounted on said base member, a metallic cup-shaped cover telescoped upon said base member to overlie said resistance varying means, a flexible band of insulation disposed around the inner face of the side walls of said cover, an edge of said band forming a yieldable bearing shoulder to engage said base member, a plurality of tongues extending from the free edge of said cover adapted to engage said base member to hold it in firm engagement with said yieldable bearing shoulder to effectively seal said unit.

6. In combination, a variable resistance device comprising a base portion having a resistance and resistance varying means mounted thereon, a cover member therefor comprising an end wall, a side wall depending therefrom, said side wall having an irregular edge composed of apertures and ears, a flexible insulating strip disposed adjacent the inner face of said side wall spacing said cover from said base, said ears being crimped inwardly to engage said base portion to retain said cover thereon.

7. A variable resistance unit comprising a base member having a peripheral projection thereon, resistance varying means mounted on said base member, a shield telescoped snugly upon said base to overlie said resistance varying means, said shield comprising an end wall with side walls depending therefrom, a notch in the free edge of said side walls registering with said projection to prevent rotative movement between said shield and base member, a plurality of ears integral with said side walls depending from said free edge, a cylindrical band of insulation surrounding said resistance varying means disposed entirely within said shield to forceably bear upon said base member adjacent the edge of its inner face, said ears being bent inwardly to engage the outer surface of said base member whereby said forceable engagement is maintained.

8. In a combined variable resistance and switch unit, a base member having resistance varying

and switch actuating means mounted thereon, a cup-shaped metallic cover telescoped upon said base member to overlie said resistance varying and switch actuating means, a switch device mounted upon the end wall portion of said cover having a controller projecting therethrough, insulating means disposed between said base member and the end wall portion of said cover for effecting a predetermined spaced relation therebetween to permit cooperation between said controller and said switch actuating means, and a plurality of fastening tongues extending from the free edge of said cover bent to engage said base member whereby the integrity of the unit thus formed is preserved.

9. A rheostat comprising a base of insulating material, a peripheral extension on said base having extending edges, a plurality of terminal members, a plurality of recesses in said extension wherein each recess has a terminal member complementary therein, a cup-shaped metallic casing for said rheostat including a plurality of holding and positioning members extending from a peripheral edge of said casing, and two of said positioning members located immediately adjacent the edges of said peripheral extension whereby the casing is located in a predetermined position on said base.

10. In a combination rheostat and snap switch unit, a single control shaft for the unit, a base of insulating material, a resistance element mounted upon said base, a peripheral extension on said base having a plurality of grooves therein, a plurality of complementary electrical terminal members interfitting into said grooves, a contact member for selectively engaging said resistance element, means for moving said contact member from said control shaft, means for operably connecting said terminal members to said resistance element and said contact member, a substantially cylindrical housing member having one end substantially closed, said substantially closed end having a small opening therein, a snap switch casing securely fastened to the substantially closed end of said cylindrical member whereby the snap-switch casing overlaps the said small opening, snap switch mechanism, a fork-like trigger of said snap switch mechanism projecting through said small opening, an eccentric for transiently engaging said fork-like trigger and suitably connected to said control shaft, a plurality of holding and positioning members extending from the peripheral edge of the open end of said cylindrical housing member, and two of said positioning members located immediately adjacent the edges of said peripheral extension whereby the cylindrical member is located in a predetermined position on said insulating base so that the snap switch trigger may be actuated by said eccentric.

NEWTON C. SCHELLENGER.
